UNITED STATES PATENT OFFICE.

WALTER J. MERRY, OF PHILADELPHIA, PENNSYLVANIA.

RESILIENT HEEL FOR BOOTS AND SHOES.

1,098,162.

Specification of Letters Patent.

Patented May 26, 1914.

Application filed November 28, 1913. Serial No. 803,631.

To all whom it may concern:

Be it known that I, WALTER J. MERRY, a citizen of the United States, residing at Philadelphia, in the county of Philadelphia and State of Pennsylvania, have invented certain new and useful Improvements in Resilient Heels for Boots and Shoes, of which the following is a specification.

My invention relates to improvements in resilient heels for boots and shoes, the object of the invention being to provide in a rubber heel at its point of greatest wear, a plurality of relatively small coiled springs which will prevent undue wear at such point, yet will not interfere with the resiliency but rather augment the same.

A further object is to provide an improved arrangement of coupled coiled springs which are embedded in the material 20 of the heel with the extreme ends of said springs adapted to contact with the ground and to act as anti-skids to prevent slipping, which frequently occurs when the heels become smooth.

With these and other objects in view, the invention consists in certain novel features of construction and combinations and arrangements of parts as will be more fully hereinafter described and pointed out in the 30 claims.

In the accompanying drawings: Figure 1 is a top plan view illustrating a heel embodying my improvements. Fig. 2 is a view in section on an enlarged scale on the line 2-2 of Fig. 1, and Fig. 3 is a bottom plan view of my improved heel.

1 represents the heel which is of rubber or other composition commonly employed in the manufacture of resilient heels. Located diagonally across the heel, adjacent its rear end where the greatest wear comes upon the heel, I provide a plurality of coiled springs 2 which are embedded in the material of the heel. These springs 2 are connected at their upper ends. A preferable arrangement is shown clearly in Fig. 2, in which two of the springs are formed by a single piece of spring wire, the connecting portion thereof indicated by the reference number 3. The third spring has one end extended as shown at 4 and connected to its adjacent coiled spring. By thus connecting the coils they are maintained in parallelism while the rubber of the heel is molded around the same and comprise a single spring cushion:

As seen most clearly in Figs. 2 and 3, the extreme lower ends 7 of the coils are exposed, so that they act to grip the ground and prevent slipping. In walking, the coiled springs act to cushion the tread and contract and expand with the contraction and expansion of the heel. They, however, prevent undue wear of the composition of the heel as they reinforce the heel at the point of greatest wear so that the life of the heel is greatly lengthened, and its resilient qualities greatly improved.

While I have described a preferred arrangement of springs, I would have it understood that I may vary the number of 70 these springs and may locate them at other points, either on a heel or sole where the greatest wear is had, and hence I do not limit myself to the precise details set forth, but consider myself at liberty to make such 75 changes and alterations as fairly fall within the spirit and scope of the appended claims.

Having thus described my invention, what I claim as new and desire to secure by Letters Patent is:

1. A heel composed of yielding material having embedded therein a plurality of vertically disposed parallel coiled springs, the lower ends of said springs exposed at 85 the lower surface of the heel, substantially as described.

2. A heel composed of yielding material having embedded therein a plurality of vertically disposed parallel coiled springs, the 90 upper ends of said springs being connected, and the lower ends of said springs exposed at the lower surface of the heel, substantially as described.

3. A heel composed of yielding material 95 having embedded therein a plurality of vertically disposed parallel coiled springs, said coiled springs located adjacent the outer rear edge of the heel at the point of greatest wear and connected at their upper ends, and 100 the lower ends of the coils exposed at the surface of the heel, substantially as described.

In testimony whereof I have signed my name to this specification in the presence of 105 two subscribing witnesses.

WALTER J. MERRY.
